MIXING METHOD AND APPARATUS

George W. Newton, Baltimore, Md., assignor to
 Crown Cork & Seal Company, Inc., Baltimore,
 Md., a corporation of New York

Application February 1, 1939, Serial No. 254,102

8 Claims. (Cl. 259—54)

The present invention relates to a mixing apparatus and method, and, more particularly, to an apparatus and method for mixing beverages such as "soft drinks" in the individual containers in which they are sold.

In the bottling of carbonated beverages, it is usual to first flow a quantity of syrup into the bottle or other container, and to then fill the remainder of the container with carbonated water. Machines have heretofore been developed and used for mixing the relatively heavy syrup with the upper strata of carbonated water. However, such prior machines have not been altogether satisfactory, due to the fact that even with the most thorough mixing which such machines can give the bottle contents, it has still been possible for an almost imperceptible layer or coating of syrup to adhere to the wall of the lower portion of the bottle; that is, the portion of the bottle in which the syrup is originally placed.

Aside from possible improper flavor resulting from the lack of complete distribution of syrup, an objection to such a coating of syrup has occurred in plants where light sensitive inspecting mechanisms are used to scan the bottle for the purpose of ascertaining whether any foreign matter is present in the bottle contents. One widely used inspection machine rotates the bottle, and then holds the bottle against rotation as its contents continue to rotate, and while the bottle is moving past a photo-electric cell. By this arrangement the entire contents of the bottle are slowly swirled in front of the photo-electric cell. In order to be completely effective in detecting extremely small fragments of foreign matter in the bottle contents, the inspection mechanism must be so sensitive to the passage of light through the bottle that it will also respond to the shadowed or darkened area created in the lower portion of the liquid when the syrup left upon the wall of the bottle by prior mixers is moved off the bottle wall into the liquid due to the rotation of the bottle. The result is that such bottles may be discarded by the inspection mechanism, causing an entirely unnecessary waste.

The principal object of the present invention is to provide a mixing apparatus and method which will thoroughly mix the contents of a container and, more particularly, will thoroughly mix all syrup in a carbonated beverage container with the carbonated water in the container.

It has been found that the removal of all syrup from the wall of a bottle and its thorough dis-

tribution throughout the contents may be accomplished by tilting or inverting the bottle, and then rapidly spinning the bottle or other container about its longitudinal axis and permitting the contents of the bottle to spin while the bottle is stationary. The initial rotation of the bottle to cause the contents to spin, and the subsequent operation of permitting the bottle to be stationary or rotate at a lower speed while the contents continue to spin, causes the walls of the bottle to be thoroughly washed or scoured by the still spinning contents, so that no syrup will be left coated on the bottle wall.

In some instances, the spinning may be performed prior to tilting, or the spinning may occur both before and after tilting. Also the position of the bottle during spinning may be other than upright and in a vertical plane.

Another object of the invention is to provide a container clamping device including means which will enable the container to rotate at high speed on its longitudinal axis without possibility of the container falling from the clamping device.

A still further object of the invention is to provide a bottle clamping device which is adapted to securely clamp containers of various sizes.

Other objects and advantages of the invention will be apparent from the following specification and drawings, in which drawings:

Figure 1 is a plan view of a machine of the present invention, portions of the machine being shown in horizontal section;

Figure 2 is a vertical sectional view on the angled line 2—2 of Figure 1;

Figure 3 is a vertical sectional view of a bottle clamping device;

Figure 4 is a horizontal sectional view on the line 4—4 of Figure 3, and

Figure 5 is a horizontal sectional view on the line 5—5 of Figure 3.

The numeral 10 designates the base of the machine in which is journalled a rotary table 11. The base 10 also supports a stationary work table 12 in front of the rotary table 11. A straight line 13 moves across one side of the worktable 12, this conveyor moving bottles or other containers to the present machine from a filling machine. A continuously rotating infeed dial 14 is mounted upon the worktable 12 to remove bottles or other containers from the conveyor 13 and position them upon the container supporting elements 15 carried upon the rotary table 11. An outfeed dial 16 is also provided upon the worktable 12 to remove successive con-

ainers from the container supports 15 of the rotary table and position them upon an outfeed conveyor 13a for removal from the machine. A guide plate 12a of usual construction cooperates 5 with the dials 14 and 16 to direct movement of the bottles. The structure described above is disclosed in Patent No. 2,117,226, issued to Robert J. Stewart on May 10, 1938, for Mixing apparatus.

Each of the container supports 15 is similar to 10 the container supports disclosed in the above-mentioned Stewart patent, in that it comprises a bottle supporting platform portion 20 including an inwardly and normally upwardly extending shank 21 which is fixed to a horizontal stub shaft 15 22 journaled in a housing 23 secured to the upper end of a standard 24 fixed on the upper surface of the rotary table 11. Each standard 24 partially encloses a vertical shaft 25 which has a pinion 26 secured to its lower end and beneath 20 the rotary table 11. The rotary table is fixed to a hollow vertical shaft 27 journaled in the base 10 and is rotated through any suitable driving means, not shown. Such rotation of the rotary table 11 causes the pinions 26 to move along 25 and about a stationary element or ring 28 having gear teeth provided on a portion of its periphery, the engagement of the teeth of the pinions 26 with the gear teeth on the ring causing the shafts 25 to be rotated. Each shaft 25 is geared 30 to the corresponding stub shaft 22 through beveled gearing within the housing 23 so that the stub shaft 22 will also be rotated to move the bottle support 15 through a vertical plane substantially radial with respect to the rotary 35 table 11.

As is the case in the structure disclosed in the above mentioned Stewart patent, each bottle supporting element 15 includes a clamping arm 30 mounted upon a vertical rod 31 which rod is 40 slideable in a bore 32 in the shank 21 of the bottle supporting element. The vertical rod 31 and clamp 30 carried thereby are urged downwardly to clamp the bottle by a spring 33 mounted in the bore 32. The upper end of spring 33 bears 45 against the upper portion of the bore 32, while the lower end of the spring bears upon a block 34 fixed to the lower end of rod 31. Block 34 has a sliding fit in the lower end of the bore 32 and has a roller 35 journaled therein. As is the 50 case in the Stewart machine, the clamping arm of the container supporting element will be raised during the time that a container supporting element is adjacent the worktable 12 so that the container then held clamped on the element 15 55 may be removed by the outfeed dial 16 and another container placed upon the element by the dial 14. The clamping device is raised during this interval by reason of the fact that the roller 35 on rod 31 will contact with a shelf-like cam 60 track 36 indicated in Figure 1. The cam track 36 is supported upon a segmental plate 37 secured to a stationary post 38 which projects up through the hollow and rotatable shaft 27 as best shown in Figure 2.

In order to permit a container to spin or rotate 65 about its longitudinal axis so that the container contents will spin, the platform 20 of each container supporting element 15 is rotatable with respect to the horizontal extension 40 of the shank 21, as shown in Figures 3 to 5. Referring 70 to these figures, it will be observed that the horizontal extension 40 is provided with a bore 41 adapted to receive a sleeve 42. Sleeve 42 is provided intermediate its length with an annular 75 exterior groove 43 with which a locking pin 44

is adapted to engage. Locking pin 44 is rotatable in a transverse bore 45 in the horizontal extension 40 and includes a cut-out portion 46 which will lie flush with the surface of bore 41 when the pin 44 is manually rotated by a handle 47 in a counter-clockwise direction from the position shown in Figure 3. Pin 44 has a sleeve 48 fixed to its end opposite the handle 47, which sleeve has one end of a coil spring 49 secured therein, the opposite end of spring 49 being secured in the extension 40. The coil spring 49 urges the pin 44 in a clockwise direction (Fig. 3) thereby urging the non-cut-away portion of the pin 44 into the bore 41 as shown in Figure 3 and into engagement with the annular groove 43 of sleeve 42 seated in the bore 41.

Sleeve 42 has a bearing sleeve 50 mounted within the same, the two sleeves being locked together by a transverse pin 51 as best shown in Figure 5. The shank 54 of the bottle platform 20 is rotatable in the bearing sleeve 50. Shank 54 is hollow and has a hardened headed pin 55 fixed at the lower end of the bore 56 thus provided. The head of pin 55 extends beneath the bearing sleeve 50, so that the shank 54 may not move upwardly with respect to the sleeves 42 and 50. The lower end of the outer sleeve 41 may be closed by a hardened disc 57. The lower surface of the head of pin 55 is rounded to co-act with disc 57 with a thrust bearing effect.

A coil spring 58 is positioned in the bore 56, the lower end of coil spring 58 resting on the pin 55 and its upper end bearing against a bottle seat disc 59 within the bottle platform 20, normally urging this disc upwardly so that its upper surface will lie flush with the upper surface of the body of platform 20. Disc 58 is provided with an annular shoulder 60 extending beneath an overlying flange 61 of the platform 20 so that the upward movement of the disc 59 will be limited. The upward inner edge of the shoulder 61 may be beveled as shown in Figure 3 to center a bottle upon the disc 59 when the bottle is forced downwardly with the disc 59 by the descent of the clamping arm 30.

The periphery of each platform 20 is flanged to form a pulley to engage an endless belt as hereinafter described.

It will be noted that each bottle platform 20 is readily removable from the horizontal extension 40 of the shank 21 simply by slightly rotating the corresponding locking pin 44 to such position that the cut-away portion 46 of the pin will be opposite the annular groove 43 of the bottle holder. It is desirable to have the bottle platforms 20 removable from the horizontal extensions 40 in order that a bottle platform with a seating disc 59 to fit the base of each bottle of a standard size may be provided for each bottle supporting element 15.

The clamping arm 30 of each bottle supporting device 15 is of a form shown in Figure 3. That is, each clamping arm 30 is provided with a socket 65 having a sleeve 66 keyed therein by means of a transverse pin 67. Each sleeve 66 has a bottle engaging fitting 68 rotatably mounted therein, the fitting 68 being hollow and having a hardened headed pin 69 fixed in its upper end, the head of the pin resting upon the upper end of the journal sleeve 66 when no bottle is engaged by the clamping arm. When the clamping arm is in engagement with a bottle, the upper and rounded surface of the head of the pin will bear upon a hardened plate 69a, these two elements thereby serving as a thrust bearing. The

lower portion of fitting 68 is skirted as indicated at 70 to provide a centering bell adapted to bear upon the cap secured to the mouth of the bottle. The sleeve 66 and the fitting 68 are readily removable from the bore 65 by removal of the pin 67, but since bottles of different sizes are ordinarily provided with caps of like sizes, there is ordinarily no necessity of disassembling the clamping head structure.

When a container is placed upon the rotatable platform 20 of a bottle supporting element 15 by the infeed dial 14, the clamping arm 30 of the bottle holder 15 will be raised due to the fact that the corresponding roller 35 is bearing upon the shelf-like cam track 36. Because of the continuing rotation of the rotary table 11, the bottle holder 15, moving in a clockwise direction (Fig. 1) will so move that its roller 35 will pass off cam track 36, permitting the clamp arm 30 to descend. This downward movement of the arm 30, induced by spring 32, will cause the bottle to move the bottle supporting disc 59 downwardly against the action of spring 58 so that the lower edge of the bottle will be pressed against the beveled surface 61 and thereby held against sidewise movement. Immediately thereafter, the pinion 26 of the bottle supporting element 15 will engage the lead-in end of the gear teeth upon ring 28 so that the bottle supporting element 15 will be rotated end over end in a plane radial with respect to the axis of rotary table 11. The machine illustrated is of such diameter that each bottle will be rotated through three complete revolutions end over end.

At the completion of these rotations, a roller 75 mounted on a pin 76 fixed to a rearward extension 77 of the element 15 will move into an upwardly facing U-shaped cam track 80 formed on the segmental plate 37. At this moment, the pinion 26 of the bottle supporting element 15 will come opposite a plain or non-toothed portion 81 of the toothed ring 28. The engagement of the roller 75 in the cam track 80 will maintain the bottle supporting element in upright position, with the container in a corresponding position, and at the same moment the periphery of the bottle platform 20 will contact with the inner runs of a pair of superposed endless belts 85. Belts 85 are continuously moving about a take-up pulley 86 and a driven pulley 87 so that the platform 20 and the bottle carried thereby will spin, the bottle rotating on its vertical axis. Driven pulley 87 is rotated by a belt 88 driven by a pulley 89 carried by the vertically arranged shaft of a motor 89a, motor 89a being secured to a plate 90 pivoted at 91 to a vertical wall of the worktable 12. The pulley 89 is of variable speed type, i. e., consists of two discs having convex opposed surfaces, the two discs being pressed together by an axially arranged spring. The distance between the axis of the motor 89 and the axis of pulley 89, journaled on the worktable, may be varied by swinging the plate 90 by means of a horizontally positioned threaded rod 92 which extends to the forward portion of the worktable 12. Such movement of the motor will vary the speed of rotation of driven pulley 87, because the driving diameter of pulley 89 will thereby be varied, due to the resultant movement toward or away from each other of the discs forming pulley 89.

The endless belts 85 are held under tension by reason of the fact that the take-up pulley 86 is mounted on a swinging arm 95 urged in a direction to tighten the belts 85 by a spring 96

positioned on a pin 97 extending between the free end of arm 95 and a bracket 98 secured to the base of the machine.

As indicated in Figures 2 and 3, each endless belt 85 is preferably of substantially double V form, and the periphery of each bottle platform 20 includes a central flange as well as upper and lower flanges to engage the two belts. By this arrangement, initial slippage of the container platform 20 with respect to the rapidly moving 10 endless belts is reduced.

Immediately a platform 20 comes into engagement with the endless belt, the platform 20 and the bottle or other container mounted thereon will begin to rotate, moving the bottle with respect to its contents so that a scouring action will be had upon the inner surfaces of the bottle. The contents of the bottle will then begin to rotate with the bottle itself, this rotation continuing until the bottle platform 20 moves from 20 contact with the opposite end of the inner run of the belt 85. When the bottle platform moves out of engagement with the belt, it will cease rotation due to peripheral contact with a friction block 99 positioned on the inner surface of the 25 stationary table 12 and just past the driven pulley 87. Contact of the periphery of a platform 20 with the block 99 will cause the platform to discontinue its rotation, so that the bottle will stop rotating. However, the contents of the bottle will continue to rotate for a short time thereafter, resulting in a further scouring action upon the walls of the bottle.

The belt 85 is moved at a sufficiently high speed to rotate each container at a speed ranging from 35 800 to 1500 revolutions per minute. However, it is to be understood that the speed range stated is merely set forth for purpose of illustration, and that either a higher or lower speed of rotation may be necessary in some instances, depending 40 upon the size and shape of the bottle, and the consistency of its contents. In short, the speed of rotation while relatively high, is to be such as to attain the object of the invention, i. e., a thorough mixing of the bottle contents, including the removal of all syrup deposit from 45 the bottle wall.

As shown in Figure 1, the cam 80 extends sufficiently far along the path of travel of the bottle holding elements that the latter will be held upright while it moves adjacent the outfeed dial 16 and the infeed dial 14. Also, the stop block 99 is positioned in advance of the lead-in end of cam 80 so that the spinning of the container will be stopped before the clamping 55 arm 30 can be lifted by cam 36, which raising occurs just prior to engagement of the bottle by dial 16.

By first imparting a tilting and uprighting or end over end movement to the container, the syrup and water within the bottle are thoroughly mixed, except for any thin layer of syrup which may coat the walls of the base portion of the bottle. Then, by causing the bottle to spin with respect to its contents, then permitting the contents to spin, and subsequently stopping the spinning of the bottle while the contents continue to spin, any layer of syrup which may have previously been present on the bottle walls is entirely removed and the syrup and water are thoroughly and uniformly mixed throughout the entire area of the bottle contents. Due to the fact that the interiors of few, if any, bottles are perfectly round throughout their entire height, and also because many bottles have their walls 70

curved in a vertical plane, a mixing action will take place even while a bottle and its contents are spinning together. By the apparatus and method of my present invention, then, a beverage of better flavor is provided and the contents are in such a state that the bottle cannot possibly be rejected by a light responsive inspection machine because of lack of uniformity of the beverage mixture.

10 As heretofore stated, the spinning may be performed prior to tilting as in my application for Mixing method and apparatus, filed July 29, 1938, Serial No. 222,042. Also, the gear teeth upon the ring element 28 may be so arranged 15 that the bottle will be in inverted position when the spinning occurs, as in said prior application, or in some other position than vertical and upright.

Subject matter of my invention disclosed but 20 not claimed herein is claimed in my copending applications for Mixing method and apparatus, Serial No. 222,042, filed July 29, 1938, and Serial No. 282,871, filed July 5, 1939.

25 It will be understood that the terminology used in the specification is for the purpose of description alone, and that the scope of the invention is indicated by the following claims.

I claim:

30 1. In a mixing apparatus, a base, a rotary table, a container supporting element journaled on said table for tilting movement of a container with respect to said table, means to deliver a container to and remove the same from said element, said element including container gripping means rotatable with respect thereto, means to move said container supporting element to tilt the container, means to rotate said gripping means to spin the container about its longitudinal axis, and means to stop spinning movement of 35 the container, whereby the contents will continue to rotate relative to the container.

40 2. In a mixing apparatus, a base, a rotary table, a container supporting element journaled on said table for tilting movement of a container in a plane substantially radial with respect to said table, means to deliver a container to and remove the same from said element, said element including container gripping means rotatable with respect thereto, means to move said container supporting element in a plane substantially radial with respect to said table to tilt the container, means to rotate said gripping means to spin the container about its longitudinal axis, and means to stop spinning movement of the container, 45 whereby the contents will continue to rotate relative to the container.

45 3. A container supporting element for a beverage mixing apparatus comprising a bracket including upper and lower arms one of which is movable with respect to the other to engage and clamp a container, a downwardly facing container engaging member carried by and rotatable with respect to said upper arm, an upwardly fac-

ing cup-like housing member carried by and rotatable with respect to said lower arm, a central plate in said housing, and yieldable means to normally hold said plate flush with the upper edge of said housing.

5 4. The method of mixing the contents of a beverage container which comprises successive steps of tilting the container and spinning the container about its longitudinal axis at a relatively high speed of the order of several hundred revolutions per minute while maintaining the container against tilting movement and positively interrupting the spinning of the container whereby the contents will continue to rotate relative to the container.

10 5. The method of mixing the contents of a beverage container which comprises successive steps of repeatedly tilting and uprighting the container and spinning the container about its longitudinal axis at a relatively high speed of the order of 20 several hundred revolutions per minute while maintaining the container against tilting movement and positively interrupting the spinning of the container whereby the contents will continue to rotate relative to the container.

15 6. The method of mixing the contents of a beverage container filled with syrup and water which comprises repeatedly tilting and uprighting the container, and then spinning the container about its longitudinal axis while maintaining the same against tilting movement, the speed of spinning being of the order of several hundred revolutions per minute whereby to be sufficiently high to remove syrup deposit from the container wall.

20 7. An apparatus for mixing the contents of a beverage container comprising a rotary table, a container supporting element, means on said table to support said element for movement in a plane substantially radial with respect to said 40 rotary table, said supporting means including container gripping means rotatable with respect thereto, means to repeatedly move said element in said plane throughout one portion of its movement with said rotary table in a manner to continuously agitate the contents of a container carried by said container supporting element, and means to spin said gripping means and container at a relatively high speed of the order of several hundred revolutions per minute about its longitudinal axis and with respect to said container supporting element during another portion of its movement with said table.

25 8. In a bottle mixing apparatus, the combination with a traveling member, of a container supporting element mounted to move on said traveling member in a plane transversely thereto, means for repeatedly moving said supporting element to tilt and upright the container supported thereby, and means for rotating the container on 50 said supporting element while the same is in its upright position.

GEORGE W. NEWTON.
